ASHTRAY

Fred Visger Barker, Alexandria Bay, N. Y.

Application January 8, 1938, Serial No. 183,985

5 Claims. (Cl. 131—235)

This invention relates to an ashtray that possesses novel features of construction for extinguishing the ignited end of a cigarette, either automatically when the cigarette has burned a predetermined distance or alternatively by the action of the smoker inserting the lighted end into a suitably provided space.

More particularly the invention resides in an ashtray construction which broadly comprises two substantially parallel plates into which a cigarette may be inserted or into which it will slide and when between the plates will be extinguished.

The conventional ashtray has usually been provided with means for resting an ignited cigarette thereon, for receiving the ashes but when the smoker desires to extinguish a cigarette he must press the lighted end against the bottom of the ash tray to break the ignited portion from the unburned tobacco. Frequently a cigarette is laid down ad forgotten in which case it may fall off the ash tray and burn the table on which the ash tray is supported or drop on to the carpet or rug, causing combustion there. In many instances, pressing the end of the cigarette firmly against the ashtray is ineffective and the cigarette continues to smolder until it has been completely burned up adding to the smoke in the room and often spreading the burning action to other cigarette butts in the tray.

Various means have been heretofore suggested for overcoming these difficulties, as for example, cigarettes have been firmly gripped in gripping elements which hold the cigarette in position and devices have been provided for inserting the cigarette therein to extinguish the ignited end. However, most of these devices are of a type that are quite complicated and the average smoker, rather than use such ashtrays as they are designed to be used, places his cigarette thereon in the normal manner and the effective action of the holders or extinguishers are lost.

This invention seeks to provide an ashtray which, in addition to providing the usual functions of a support for the cigarette and a holder to receive the ashes, supplies safety features for the extinguishing of the cigarette and also for preventing its continued smoldering if it is left on the ashtray.

The construction herein provided is to general outward appearances quite similar to conventional ashtrays, yet, in its normal use the smoker naturally places the cigarette thereon so as to make the ash tray automatically effective to ex-

tinguish the cigarette if it is left there for a sufficient length of time. Unless the cigarette is apparently abandoned, there is no extinguishing action and the cigarette continues to burn in its normal manner avoiding the undesirable effect of a quenched cigarette should the smoker desire to continue his smoking after having left it on the ash tray for a short interval of time.

The invention also provides a very convenient extinguishing means which can be used if the smoker desires to intentionally extinguish the end of the cigarette without the necessity of putting his fingers into the ashes that are gathered at the bottom of the ashtray.

An important object attained by this invention is a construction useful for ashtrays whether of a conventional table or stand type or of a type to be used in a vehicle, as for example, on the dashboard of an automobile. The same principle of construction is applicable to either or all types of ashtrays.

To obtain these and related objects which will be apparent hereinafter or specifically set forth, this invention comprises an ashtray of a construction illustrated as to certain preferred embodiments in the accompanying sheets of drawings wherein:

Figure 1 is a plan view showing the ashtray and a cigarette partly burned as well as an extinguished cigarette;

Figure 2 is a view in cross-section of the ashtray illustrated in Figure 1;

Figure 3 is a modified form of ashtray of a type similar to that shown in Figures 1 and 2;

Figure 4 is a cross-sectional view of an ashtray embodied in a drawer which can be mounted on the dashboard or other portions of a vehicle body; while

Figure 5 is a cross-sectional view along the line 5—5 of Figure 4 showing the ashtray construction in plan.

Referring first to Figures 1 and 2, wherein corresponding parts have similar reference numerals, the ashtray as therein embodied comprises a base 2 which may be of any desired shape or construction and is conveniently made of metal with a felt bottom to prevent scratching any surface on which it may be laid. As will be evident, the base 2 may be attached to a pedestal. Projecting upwardly from the base 2 is a cylindrical member 4 that serves as a support for the remaining portions of the ashtray which may comprise a plurality of substantially parallel conically shaped discs. The lower conical disc 6 has a central aperture sufficiently

large to receive the cylindrical member 4 to which it may be fastened by suitable fastening means. Above the disc 6 is a second conical disc 8 conveniently mounted on the top of the cylindrical member 4 or may be a single piece forming the base, cylindrical member and conical disc in which case the cylindrical member 4 would be open at the top. In the embodiment illustrated in Figures 1 and 2, the upper conical disc 3 is a true cone and may form a support for a match box holder 10.

In the preferred construction, the outer edge 12 of the lower conical disc 6 and the outer edge 14 of the conical disc 8 are in substantially the same horizontal plane as compared to the base 2. These edges may be smooth or have depressed or cut-away portions to reduce the tendency of a cigarette to roll off the ashtray. With this arrangement a cigarette C when laid on the ash tray in the normal manner as seen in Figures 1 and 2, will rest on the two edges 12 and 14. The lighted end L of the cigarette C will be above the upper conical disc 8 and the ashes would normally be discharged into this receptacle. If however, a cigarette C is laid in the position shown in Figures 1 and 2, and the lighted portion continues to burn, it will gradually reach the point B just above the edge 14.

When the ash has progressed back to this point, the edge 14 will not support the paper of the cigarette but will be against the ash which, being much weaker than the paper and tobacco portion, will break by the weight of the cigarette and it will fall down into the receptacle formed by the lower disc 6 which, being on an incline, will cause the cigarette to slide so that the lighted end is between the discs 6 and 8. This position is illustrated by the cigarette C' in which the ignited end is in between the plates 6 and 12 where, because of the restricted supply of air, freedom from air currents, and the loss of heat to the metallic conical discs 6 and 8, it will be readily extinguished.

The modified construction illustrated in Figure 3 dispenses with the separate base member 2 and comprises two inverted frusto-conical members the lower of which is designated as 16, which may have a slightly depressed base portion 18. The upper frusto-conical member 20 may be spaced from the lower frusto-conical member 16 by a cylindrical washer 22 and the two frusto cones held in their proper relationship by a threaded screw 24 inserted through a countersunk opening 26 in the base member 18. The threaded screw 24 is screwed into an upright handle 28 that may serve simply as a decorative handle for the ash tray or a support for a match box or book of matches.

The construction shown in Figure 3 produces the same result as that shown in Figures 1 and 2 in that a cigarette C, when supported in the position shown with its ignited end L above the upper frusto-conical member 20, will, when the ash has progressed back to B above the edge 30 of the upper frusto-conical member 20, pivot about the upper edge 32 of the lip 33 on the lower frusto-conical member 16, and slide or fall into the compartment formed between the two frusto cones 16 and 20 as shown by the position of the cigarette identified as C'.

Instead of depending upon the ashtray to automatically extinguish the cigarette, the smoker may, if he desires, insert a cigarette between the two frusto-conical members in the position

shown by the cigarette C' and thereby cause it to become extinguished.

The conical member or the frusto-conical members of the embodiments illustrated in Figures 1, 2 and 3 may be considered as generated by the rotation of a line about an axis in which the rotating line is at an angle to that axis. In the embodiment illustrated in Figures 1 and 2 the generating line for the cone 8 and the generating line for the frusto-conical member 6 are almost exactly parallel while the generating lines for the frusto-conical sections 16 and 20 of Figure 3 are substantially although not exactly parallel. This latter construction permits a slightly more ready insertion of the ignited end of the cigarette between the two members. However, in both constructions, the generating lines of the two related surfaces are substantially parallel and spaced apart an average distance equal to the diameter of a cigarette.

A further embodiment of the invention is illustrated in Figures 4 and 5 wherein the principles of this invention are applied to an ashtray designed particularly for mounting on the dashboard of a vehicle. The dashboard of the vehicle or a plate for surrounding an opening made into the dashboard of the vehicle and identified by the reference numeral 40 carries a rectangular receptacle 42 closed except at the opening in the dashboard or plate 40. This receptacle 42 is of such size and shape as to receive a drawer formed in the manner hereinafter described. The front of the drawer is a plate 44 to which is attached a handle 46 held in position by a screw 48.

Attached to the lower edge of the drawer plate 44 as at 50 is a strip of metal identified as 52. This strip of metal 52 projects substantially at right angles to the plate 44 for the length of the receptacle 42 when it is bent upwardly at the point 54, continuing in that direction for the height of the receptacle 42 where another bend 56 is made back toward the front plate 44. A short distance from the rear of the receptacle 42 the strip 52 is bent downwardly as at 58 and a short distance from this point the strip is bent obliquely toward the lower rear of the receptacle 42 as at 60. Adjacent the bends 54, the strip 52 makes a smooth bend of relatively large radius at 62, from which point it continues toward the front plate 44 in a generally upward direction to its end 64.

It will thus be seen that the strip 52 from the point 50 where it is attached to the plate 44 to its end 64 forms the bottom, rear and a portion of the top of a drawer formed within the receptacle 42 and also provides an upper plate 66 between the bends 60 and 62 and a lower plate 68 substantially parallel thereto between the bend 62 and the end of the strip 52 at 64. These plates 66 and 68 are not coextensive but the lower plate 68 projects substantially beyond the upper limit of the plate 66. The drawer is completed by two side members 70 and 72 to form a closed receptacle except for the open top between the bend 58 and the front plate 44. The ashtray may be drawn from its receptacle 42 so that substantially the entire open top is exposed, its outward movement being limited as by a catch 74 which will engage the bend at 58.

This construction as illustrated in Figures 4 and 5 represents a very desirable form of ashtray for a vehicle, since when it is withdrawn the smoker may readily deposit ashes into the drawer and they will, for the most part, fall into the general compartment 76. However, when it is desired to

dispose of the cigarette, it is simply dropped into the ashtray drawer so that it falls on the plate 68 in which case it will slide or roll down in between the plates 66 and 68 where it will be extinguished. It is not necessary for the driver to observe where he places the cigarette although he may place it with ignited end in, in the position shown in C' of Figure 5, or he may simply drop it on the plate 68 in which case it will roll and 10 assume a position similar to that illustrated by the cigarette C' in Figure 4.

As in the case of the cones or frusto cones of Figures 1, 2 and 3, the two flat plates 66 and 68 of Figure 4 may be considered as generated by the 15 movement of two lines in planes substantially parallel to each other. The closed portion formed between the plates 66 and 68 as well as by the curved portion 62, provides an extinguisher for the cigarette and is formed by two flat plates substantially parallel to each other.

In considering the several modifications or embodiments of the invention, it will be noted that the lines generating the plates which are in a plane passing at right angles to the plates are 25 substantially parallel. Considered from another angle, the two plates at their exposed ends are spaced apart slightly greater than the diameter of a cigarette while at their remote ends they are separated by a distance slightly less than the diameter of a cigarette. This construction permits the ready application of the principle herein involved for extinguishing a cigarette which may be either dropped or will slide in between the plates to be extinguished.

35 Instead of embodying the invention in a drawer as shown in Figures 4 and 5, various other types of receptacles may be employed where the ashtray is to be embodied in an accessory for a vehicle. For example, it could be pivoted or could be set 40 upright as will be apparent to those skilled in the art it being important only that the two plates 66 and 68 be arranged in a generally similar manner although their horizontal position may be varied as will be evident.

45 While the invention has been described with reference to certain preferred embodiments thereof, it will be apparent that various changes can be made from the construction herein specifically shown and described without departing from the spirit and scope of the invention.

This application is a continuation in part of my copending application Serial No. 98,386 filed August 27, 1936, for an Ashtray.

What is claimed is:

55 1. An ashtray of the character described comprising supporting means, a first plate having inclined walls on said supporting means, a second plate extending outward from said supporting means below the first plate having its outer edge 60 in substantially the same horizontal plane as the edge of the first plate, all corresponding elements of the upper surface of the lower plate and the lower surface of the upper plate being substantially parallel, said plates being spaced a distance 65 substantially equal to the diameter of the common cigarette and thereby providing a space between

said plates adapted to receive and smother a cigarette, whereby an ignited cigarette when placed in a supported position on the edges of both plates will fall into said second plate after the ash of the ignited portion thereof has separated from the body of the cigarette at the first plate. 5

2. An ashtray of the character described comprising supporting means, a first inverted conical plate on said supporting means, a second inverted 10 frusto-conical plate extending outward from said supporting means below the first plate having its outer edge in substantially the same horizontal plane as the edge of the first plate, corresponding elements of the upper surface of the lower plate 15 and the lower surface of the upper plate being parallel, said plates being spaced a distance substantially equal to the diameter of the common cigarette and thereby providing a space between said plates adapted to receive and smother a cigarette, whereby an ignited cigarette when placed in a supported position on the edges of both plates will fall into said second plate after the ash of the ignited portion thereof has separated from the body of the cigarette at the first plate. 20

25 3. An ashtray of the character described comprising supporting means, a first plate having inclined walls on said supporting means, a second plate extending outward from said supporting means below the first plate having its outer edge 30 in substantially the same horizontal plane as the edge of the first plate, portions of said plates being spaced a distance substantially equal to the diameter of the common cigarette and thereby providing a space between said plates adapted to 35 receive and smother a cigarette, whereby an ignited cigarette when placed in a supported position on the edges of both plates will fall into said second plate and in smothering relation to said first plate after the ash of the ignited portion 40 thereof has separated from the body of the cigarette at the first plate.

4. An ashtray of the character described comprising two spaced inclined plates, means closing the space between said plates at least along the 45 lower edges of said plates, said plates being co-extensive over a substantial area and separated a distance slightly greater than the diameter of the common cigarette and thereby providing a space between said plates down which a cigarette may 50 slide or roll and adapted to receive and smother a cigarette.

5. An ashtray for receiving cigarette ashes and for extinguishing an ignited cigarette comprising a first member embodying a surface generated by 55 a straight line, a second member embodying a surface generated by a straight line, said members being substantially parallel so that the generating lines when in a plane perpendicular to the two members are substantially parallel and spaced 60 apart a distance approximately that of a common cigarette to provide a space between the members into which a cigarette may be inserted or into which it will slide or roll and be extinguished. 65
